UNITED STATES PATENT OFFICE.

CLARENCE E. HARRIS, OF MILWAUKEE, WISCONSIN.

STENCIL-HOLDING APPARATUS.

1,324,044.

Specification of Letters Patent.

Patented Dec. 9, 1919.

Application filed March 3, 1919. Serial No. 280,305.

To all whom it may concern:

Be it known that I, CLARENCE E. HARRIS, a citizen of the United States, and resident of Milwaukee, in the county of Milwaukee and State of Wisconsin, have invented certain new and useful Improvements in Stencil-Holding Apparatus; and I do hereby declare that the following is a full, clear, and exact description thereof.

10 My invention relates to new and useful improvements in means for holding a stencil against a surface to be decorated.

In stenciling walls or ceilings, it is customary for two or more workmen to hold 15 the stencils in place, while another workman applies the decorating fluid. In addition to the number of workmen required in this operation, the operation of holding the stencils is exceedingly irksome and tiring, 20 this conduced to difficulty in securing labor for the operation, in addition to the normal expense of such labor.

It is therefore primarily the object of my 25 invention to provide means for mechanically holding the stencil against the ceiling or other surface to be decorated.

In stenciling a ceiling, a support for the operator and his equipment is usually afforded by scaffold boards, which are susceptible to considerable flexure as the workman moves about thereon. It is therefore a further and important object of my invention to provide a stencil holding device wherein compensation is automatically afforded for the yielding movements of the scaffold board on which it is mounted.

A further object of my invention is to 40 provide a device of this character which is fully adjustable in nature to adapt it for different sizes of stencils and for different uses to which it may be adapted, also to firmly hold a stencil against a slanting ceiling portion. A further object of my invention resides in the provision of a stencil holding unit which may be manipulated for holding a stencil either against the ceiling or wall of a room.

With the above and other objects in view, which will be apparent as the description 50 proceeds, my invention resides in the novel features of construction, combination and arrangement of parts as hereinafter described and defined by the appended claims, it being understood that changes in the precise embodiment might be made by those

skilled in the art, without departing from the spirit of the invention.

In the accompanying drawings:

Figure 1 is an end elevational view of a stencil holding device embodying my invention.

Fig. 2 is a side elevational view thereof.

Fig. 3 is a similar view showing the device adapted for use in holding the stencil against a slanting surface.

Referring now more particularly to the drawings, there is provided a support standard which comprises a lower section 5, an intermediate section 6, and an upper tubular section 7 telescopically mounted on

the rounded upper end of the intermediate section 6. The intermediate and lower sections may be of any desired nature, and in the present instance are rectangular in cross-section to afford opposed flat slide faces being held in sliding relation by suitable strap yokes 8.

One of the yokes has a set screw 9 threaded in its bight whereby the intermediate and lower sections may be held against sliding movement to adapt the device for use under differing conditions involving variable distances between the ceiling and the scaffold or other support on which the standard may be mounted.

The upper section 7 is resiliently urged upwardly by an expansile spring 10 coiled on the upper rounded portion of the intermediate section 6 and engaging the lower end of

said section 7. A clamp collar 11 is fixed on the upper end of the standard section 5 and receives a crosshead bar 12, said collar being provided with upstanding ears receiving a set screw for clamping the bar 12 against movement in the collar.

A pair of clamp collars 14, controlled by set screws 15 are mounted on the head bar 12 for adjustment longitudinally thereon and each of these clamps carries an upstanding fixed jaw 15 and a pivoted jaw 16 engaged by a clamping screw 17 for supporting a stencil holding bar 18, said bar 18 being of a length

adapted to accommodate a stencil of maximum width and being adjusted on the head bar 12 by means of the clamp bar 14 to accommodate the various ranges in length of

the stencils used.

An ordinary stencil S may be secured in any desired manner to the stencil holding bars, which, as shown particularly in Fig. 1,

have their stencil engaging faces disposed

in a plane spaced considerably above the clamp collar 11 of the standard.

To effect this securement in the present embodiment of my invention, an elongated 5 clamp plate 19 is provided for each stencil holding bar, the outer side of each plate being bent at 20 and having hinge connections 21 with the outer side of the bar. The inner sides of the plate are bent inwardly at 22 10 for most efficient clamping engagement with the stencil, and the plate is resiliently urged to clamp the edge of the stencil between it and the top face of the holding bar 18 by springs 23 coiled on the journal rod of its 15 hinge connections 21, movement of the plate 4 in removal or insertion of the stencil is effected by suitable finger pieces 24 projecting therefrom.

In operation of the device, stencil S is 20 mounted on the holding bars in the manner described, the standard is then stood upon the scaffold or other support, being adjusted in height so that the spring 10 resiliently urges the stencil bars into engagement with 25 the ceiling. Thus yielding movement of the scaffold board or other support is automatically taken up by the spring to retain these stencil holding bars in engagement with the ceiling. The device may be manipulated by 30 a single operator and with the stencil then held thereby the operator's attention may be entirely directed to applying the decorating fluid to the stencil.

When it is desired to hold a stencil to a 35 slanting ceiling as shown in Fig. 3, the support standard of the device is mounted in its usual vertical manner, and the stencil holding bars 18 are adjusted angularly with respect thereto in accordance with the slant of 40 the ceiling. To prevent slippage of the stencil holding bars on the slanting ceiling,

spurs 25 are provided at the ends of the bars, having elongated slotted shanks adjustably secured to the bars by clamping bolts 26, these spurs affording a firm engagement 45 with the ceiling without damaging the same, particularly by reason of the degree of adjustment afforded these spurs whereby they may engage vertically in the ceiling in various angular positions of the holding bars. 50

When it is desired to hold a stencil to a wall, the upper standard section 7 is removed from the other sections thus affording with the holding bars and cross-head bar, a unit 55 which may be readily grasped by one hand of the operator and wielded to apply and hold the stencil.

While I have shown and described the preferred embodiment of my invention it will be appreciated that various changes and 60 modifications of structure may be employed to meet different conditions of use without departing in any manner from the spirit of my invention.

What is claimed is:

1. A stencil holding device comprising a support standard, a transverse head bar mounted on said standard and stencil holding bars adjustably carried by said head bar.

2. A stencil holding device comprising a 70 support standard, a cross-head bar mounted on the standard, clamp collars adjustably mounted on said bar, clamps carried by said collars, transverse stencil holding bars adjustably mounted in said clamps, and means 75 for securing a stencil to said transverse bars.

In testimony that I claim the foregoing I have hereunto set my hand at Milwaukee, in the county of Milwaukee and State of Wisconsin.

CLARENCE E. HARRIS.
